Switzerland

Application August 2, 1952, Serial No. 20,885

Term of patent 7 years

(Cl. D85—8)

To all whom it may concern:

Be it known that I, Jock Francken, a citizen of the United States, residing at Villa Ly, Lugano-Suvigliana, Switzerland, have invented a new, original, and ornamental Design for a Cigarette Holder, of which the following is a specification, reference being had to the accompanying drawing forming a part thereof.

Fig. 1 is a plan view of a cigarette holder embodying my new design;

Fig. 2 is a side elevation of the cigarette holder of Fig. 1;

Fig. 3 is a view from below of the cigarette holder of Fig. 1, and

Fig. 4 is an end view from the left of Fig. 1.

I claim:

The ornamental design for a cigarette holder, as shown.

JOCK FRANCKEN.
